US00D520996S

(12) **United States Design Patent** (10) **Patent No.:** **US D520,996 S**
(45) **Date of Patent:** **** May 16, 2006**

(54) **USB FLASH MEMORY DRIVE**

(75) Inventor: **Wen-Feng Deng**, Suzhou (CN)

(73) Assignee: **BenQ Corporation**, Taoyuan (TW)

(**) Term: **14 Years**

(21) Appl. No.: **29/217,422**

(22) Filed: **Nov. 17, 2004**

(30) **Foreign Application Priority Data**

Oct. 8, 2004 (TW) 93305925

(51) **LOC (8) Cl.** **14-02**

(52) **U.S. Cl.** **D14/356**

(58) **Field of Classification Search** 361/737,
361/752; 365/200; 439/135, 136, 147, 165,
439/497, 607, 639; D14/99, 138, 218, 230,
D14/240, 242, 348, 356, 358, 367, 384, 385,

(57) **CLAIM**

The ornamental design for a USB flash memory drive, as shown and described.

DESCRIPTION

FIG. 1 is a front isometric view thereof;

FIG. 2 is a front elevational view thereof;

FIG. 3 is a rear elevational view thereof;

FIG. 4 is a left side elevational view thereof;

FIG. 5 is a right side elevational view thereof;

FIG. 6 is a top plane view thereof;

FIG. 7 is a bottom plane view thereof;

FIG. 8 is a rear isometric view shown in the exploded condition thereof;

FIG. 9 is a front isometric view shown in the exploded condition thereof; and,

FIG. 10 is a rear isometric view shown in the exploded condition thereof.
